APPARATUS FOR CLEANING OR TREATING ARTICLES

BACKGROUND OF THE INVENTION

1. Field of the Invention

The present invention refers in general to cleaning or treating apparatus and in particular to washing or treating machines for relatively small industrial parts, such as screws, nuts, bolts, etc.

Most of these industrial parts, such as bolts, screws, etc., need to be cleaned after manufacture to remove dirt, oil, greases, metal chips and the like from them before being further processed. This is conventionally done in industrial washing or cleaning apparatuses designed for this purpose and these apparatuses may be manually operated or power driven. Usually the parts are washed in a cleaning solution by immersion or spraying or both, the cleaning solution being of a type best suited to remove a certain type of sludge or other contamination from the parts.

The present invention is concerned with a power driven apparatus of this kind and conveniently the apparatus may also be used for treating industrial parts by substitution of the proper treating fluid for such processes as, for instance, rust-proofing or other coatings.

2. Description of the Prior Art

Treating machines or apparatuses of the prior art are usually large and bulky in relation to the parts to be cleaned and their construction and operation is unnecessarily complicated for the intended purpose. Usually these apparatuses employ a rotating drum container or tumbler to receive the parts and the inside of the tumbler may be provided with transporting means, such as a helix or the like to feed the parts continuously from one end of the tumbler to the other. Normally a cleaning fluid is supplied to the parts as they travel through the tumbler by means of direct immersion of the tumbler within the fluid or by spraying the parts with the fluid. In conventional power driven apparatuses in the prior art the means to rotate the tumbler and agitate the cleaning fluid for cleaning action are separated from each other and the cleaning fluid is usually drained off into the plant drainage system after usage. This complicates the installation in regards to the space needed and the location requirement for drainage of the cleaning fluid. In addition these conventional installations are usually wet due to splashing of the cleaning fluid.

Furthermore, conventional cleaning apparatuses of this type cannot be used for coating articles due to the uncontrolled splashing and other loss of fluid.

SUMMARY OF THE INVENTION

The present invention provides a novel universal-type washing or treating apparatus for relatively small industrial parts embodying certain features adapted to eliminate the primary disadvantages of the prior art. To this end the invention is comprised of a tumbler having an internal helical surface in order to receive parts for cleaning fed into one end of the tumbler and advanced to the opposite end by the helical surface when the tumbler is being rotated. A pipe extends lengthwise into the tumbler to convey cleaning fluid. The pipe is connected to a pump for connection with the supply of fluid. The tumbler is rotated by a motorized drive means. The primary feature provides for enclosing all of these components within a single normally-closed housing to protect them from splashing. The components are all arranged such as to fit within the smallest possible space making it a self-contained unit which can be placed at any convenient location in the plant since it is not dependent on drainage and fluid supply requirements. An ample amount of cleaning fluid contained in the bottom of the unit is filtered and circulated by the pump for continuous use.

The drive motors for the pump and the tumbler are likewise located within the unit but well above the fluid supply level and protected against splashing. The pipe extending within the tumbler is provided with a number of spaced nozzle openings to eject fluid at a high pressure and velocity onto the parts to be cleaned. The ejected fluid is drained back into the fluid

supply of the unit where it is filtered for reuse, the sludge removed from the parts settling at the bottom of the unit. Provisions are made that at certain intervals the collected sludge may be removed from the unit by quickly draining the fluid supply with the help of its own pump.

Instead of cleaning fluid, coating fluid may be used in the unit for the purpose of coating the parts instead of cleaning.

Accordingly, the primary object of the present invention is the provision of a novel unitary washing or treating apparatus for industrial parts which is entirely self-contained within a normally-closed housing having a shielded part-feeding chute and a clean parts discharge chute.

Another object of the present invention resides in the provision of a novel tumbler and spray pipe combination by which the parts to be cleaned are constantly tumbled and fed along the interior of the tumbler and subjected to high powered jets of cleaning fluid from the spray pipe associated with the tumbler.

A further object of the present invention is to provide in a washing apparatus for industrial parts a boxlike housing, a fluid supply sump within the housing and a filter and pump arrangement within the housing to continuously filter and circulate the fluid for washing parts fed into the housing.

Other obvious advantages and novel features will become apparent from the following detailed description in connection with the accompanying drawings illustrating a preferred embodiment of the invention.

BRIEF DESCRIPTION OF THE DRAWINGS

FIG. 1 is a perspective overall view of the present novel apparatus schematically illustrating in phantom lines parts of the interior;

FIG. 2 is an elongated cross section through the apparatus in FIG. 1;

FIG. 3 is a transverse cross section through the apparatus in FIG. 1;

FIG. 4 is an enlarged detailed view of the sump and drive mechanism embodied in the apparatus in FIG. 1;

FIG. 5 is a partial perspective view of the mechanism in FIG. 4;

FIG. 6 is a perspective detailed view of the tumbler used in the apparatus in FIG. 1;

FIG. 7 is a perspective view of a further embodiment of the apparatus in FIG. 1;

FIG. 8 is a detailed perspective illustration of the pump, pump drive and filter arrangement embodied in the apparatus in FIG. 1; and

FIG. 9 is an enlarged cross section through the spray pipe and nozzle arrangement embodied in the present invention.

DESCRIPTION OF THE PREFERRED EMBODIMENT

With reference to FIG. 1 there is illustrated a novel washing apparatus comprising an enclosure 10 in the general form of a rectangular box made up of longitudinal sidewalls 12 and 14 and front and rear walls 16 and 18 respectively closed off by a bottom 20 and top 22 so as to form a substantially-closed box-type structure. The lower portion 24 of the box structure has openings 26 and 28 in both its front wall and rear wall normally closed by removable covers 30 for servicing of the unit as will be explained hereafter.

The front wall 16 of the upper portion 32 has an opening 34 for receiving a feeding chute 36 attached thereto. Likewise, the sidewall 12 in the lower portion 24 has an opening 38 for receiving a discharge chute 40. Obviously, the discharge chute 40 may be placed in the opposite sidewall 14.

With further reference to FIG. 2, the upper portion 32 of the boxlike structure 10 receives a drum type tumbler 42 positioned in longitudinal direction of the enclosure and substantially in axial alignment with the feed chute opening 34. As seen in FIG. 6 the tumbler 42 is preferably a screen-type drum having a front opening 44 and rear opening 46. Retained within the tumbler and extending from end to end thereof is a

helical guide surface 48 in the form of a ribbon with its edge attached as by brazing or otherwise to the internal screen surfaces of the tumbler. Positioned between adjacent helices are longitudinal deflectors 50 for a purpose to be explained. Attached to the outside of the tumbler and spaced some distance from the opening 44, 46 thereof, are a pair of radial rings 52 and 54 which may be press fitted to the tumbler or attached thereto by brazing or the like. These rings 52, 54 have outer bearing surfaces for support and rotation upon opposed pairs of rollers 56, 58. Either the bearing surfaces or the rollers may be hardened but this is not a necessary requirement. The rollers are attached for rotation on pins 60 supported within brackets 62 attached in upstanding fashion so as to freely support the rollers. The brackets 62 are attached to transverse support beams 64 secured within the enclosure 10 just underneath the tumbler 42.

The tumbler 42 is rotated by the provision of a sprocket wheel 66 secured to the outside of the tumbler at one end thereof. The sprocket wheel 66 is adapted to receive a drive chain 68 which is drivingly connected to a drive motor 70 by means of a smaller sprocket wheel 72. The electric tumbler drive motor 70 is secured and supported upon a transverse support beam 74 attached within the lower portion 24 of the enclosure 10 a distance spaced from the bottom wall 20 for a purpose to become clear.

A pipe 76 extends lengthwise into the tumbler 42 from the end opposite the feeding chute 36 and is located close to the upper inner surface of the tumbler. The end 78 of the pipe 76 is attached to a flange 80 adjacent the upper edge of the chute opening 34. Located a distance from the end 78 of the pipe 76 are a number of fluid discharge openings 82 in the form of jet nozzles as seen in FIG. 9. The nozzle distance D as indicated in FIG. 2 constitutes the effective spray area as will be explained. The other end of the pipe 76 has a T-connector 84 whose end which is coaxial with pipe 76 receives another pipe section 86. The branch 88 of the T-connector 84 will be normally closed by a plug 90 which can be removed for a purpose to be described later on. The pipe section 86 extends downwardly towards the bottom 20 of the enclosure to communicate with the outlet of a pump 92 which is secured to the bottom 20 of the enclosure by means of clamps 94. The pump 92 which is preferably an impeller-type pump is driven by an electric motor 96 positioned vertically above the pump on the end of a tubular support 98 through which the drive shaft 100 of the motor extends, as seen in FIG. 5. The tubular pump-motor support 98 is stabilized in vertical position by means of a U-clamp 102 bolted to the transverse drive motor support beam 74 by nuts 104.

The inlet 106 of the pump 92 is provided with a fluid filter 108 and the bottom of the lower portion 24 is filled with a suitable cleaning fluid 110 up to a level L a small distance below the lower edge of the opposed service openings 26, 28. It will be noted that the pump motor 96 and drive motor 70 by means of their supporting structures are well above the level L of the fluid and thus their operation will not be affected by contact with the fluid 110. Likewise, the effective spray area D indicated in FIG. 2 is well in advance of the electric motors 70, 96 which are thus protected from any splashing effect upon operation of the apparatus.

Both the electric motors 70 and 96 have electrical connections (not shown) with a control panel 112 secured to the side 12 of the enclosure. The control panel has the usual "stop" and "go" switches or buttons 112 to stop or start the machine 65 and a pilot light 116 may be provided to indicate that the machine is in operation and within the control panel overload circuit breakers may be provided as is common practice to protect the motors against overloading. Once the machine is started, the operation is completely automatic except for feeding the feed chute with parts to be cleaned.

In operation, the operator starts the machine by manipulating the "go" switch to connect the tumbler motor 70 and pump motor 96 to the electric current. It then feeds the parts 75 P onto the chute 36 from which they are drawn into the enclo-

sure and thus into the tumbler 42 by gravity. The rotating tumbler carries the parts around with it and along its inner surface by means of the helical guide 48. When the parts reach the area D indicated in FIG. 2 they are sprayed by high velocity jets of cleaning fluid expelled from the nozzles 82 in the pipe 76. The velocity and relatively high pressure of the spray thoroughly rinses the parts of all contaminants such as shop dirt, metal chips, etc. Due to the tumbling action the parts will be cleaned around all their surfaces, including any internal surfaces such as found in nuts and blind holes. The cleaned parts leaving the spray area D are further conveyed along the interior of the tumbler by the helices 48 to the discharge chute 40 from which they are expelled through opening 38. During this action the cleaning fluid 110 is constantly recirculated from and back into the sump by the pump 92. The filter 108 assures that only pure cleaning fluid will be used to exit from the nozzles 82 whereas the contaminants are caused to settle on the bottom 20 of the enclosure 10.

Periodically it will be necessary to clean out the fluid sump to remove the collected contaminants. To accomplish this, the fluid 110 must be drained from the enclosure 10. With reference to FIG. 8, the plug 90 of the T-connector 84 is removed and a drain hose 112 is screwed into the branch connection 88 thereof. Thereafter, operating the pump 92 will drain the enclosure 10 of all fluid 110 through the drain hose 112 into a suitable container for reuse. After draining of the fluid 110 from the enclosure the covers 30 may be removed to clean out the bottom 20. The drained fluid 110 may then be pumped back into the enclosure for reuse together with an additional amount of fluid to compensate for any fluid loss to bring the level back to the original height.

FIG. 7 illustrates the use of a composite discharge chute 114 which may be used in place of the simple drop chute 40 to convey the parts P into a container 116 which may be located at a remote location from the machine 10.

In conclusion, the present invention provides a highly efficient, multipurpose, industrial parts washing apparatus. In an exemplary embodiment the apparatus may operate at a capacity of 120 cubic feet per hour in a 60-second cycle; that is, parts fed into the apparatus will travel through the apparatus in one minute. The high velocity spray jets may dispense the cleaning fluid at, for instance, 30 gallons per minute. The electric current to operate the machine can be conventional 110 volt AC shop current so that no additional electrical installations are necessary.

The parts will be thoroughly cleaned including all internal surfaces.

If desired, the cleaning fluid may be replaced by a coating or other solution for treatment of the parts other than cleaning.

The present invention may be embodied in other certain forms without departing from the spirit and inventive characteristic thereof, therefore, the present embodiment is to be considered in all respects as illustrative only and not restrictive, the scope of the invention being indicated by the appended claims rather than by the foregoing description.

I claim:

1. An apparatus for washing articles comprising:
a housing having a lower portion and a cover portion carried by said lower portion and enclosing said housing;
a horizontally disposed tumbler rotatably carried in said cover portion, said tumbler comprising an open drum formed of a continuous screen to allow fluid supplied thereto to drain from said drum, said drum having an internal surface provided with a helical guide means for displacing said articles from one end of said drum to an opposite end of said drum as said drum rotates;
a liquid sump in said lower portion;
drive means for rotating said drum;
a pump for said liquid having an outlet pipe extending within said drum, said outlet pipe being positioned close to the upper inner surface of said drum and having nozzle openings for forcibly directing said liquid downwardly into the interior of said drum;

said housing having inlet means carried by said cover portion and associated with said one drum end and outlet means carried by said lower portion and associated with said opposite drum end respectively for the transmission of said articles to and from said drum; and

said nozzle openings being positioned in said drum proximate said one drum end for fluidly treating said articles as said articles are displaced from said inlet means to said outlet means.

2. The apparatus as defined in claim 1 wherein said inlet means is an inlet chute carried by said cover portion and extending through said cover portion externally of said housing, and said outlet means is an outlet chute disposed in said lower portion and extending internally of said housing, said inlet chute being axially aligned with said tumbler and said outlet chute being generally at right angles thereto.

3. The apparatus as defined in claim 1 wherein said drive means for said drum and said drive means for said pump are electric motors disposed in said lower portion above the level

of said liquid sump at a position proximate said opposite end of said drum.

4. The apparatus as defined in claim 3 wherein said pump is disposed on the bottom of said lower portion within said liquid sump, and including an upwardly extending support member upon which said electric motors are disposed above the level of said liquid sump.

5. The apparatus as defined in claim 4 wherein said horizontally disposed drum is adapted to rotate about a horizontal axis, said drive means for rotating said drum comprising a chain and sprocket drive mechanism drivingly connected to one of said electric motors.

6. The apparatus as defined in claim 1 wherein said cover portion is releasably attached to said lower portion.

7. The apparatus as defined in claim 1 including a releasably attached side portion carried by said lower portion to permit access to the interior of said lower portion.
